UNITED STATES PATENT OFFICE.

HOWARD R. ROST, OF CHICAGO, ILLINOIS, ASSIGNOR TO CONTINENTAL DISTRIBUTORS,
INCORPORATED, OF CHICAGO, ILLINOIS, A CORPORATION.

DESIGN FOR A FIRE-EXTINGUISHER.

53,936.

Specification for Design.

Patented Oct. 7, 1919.

Application filed June 24, 1916. Serial No. 105,748. Term of patent 14 years.

To all whom it may concern:

Be it known that I, HOWARD R. ROST, a citizen of the United States, residing at Chicago, in the county of Cook and State of Illinois, have invented a new, original, and ornamental Design for a Fire-Extinguisher, of which the following are the specifications, reference being had to the accompanying drawing, forming a part thereof.

On the drawing:

Figures 1 and 3 are side elevations of an extinguisher embodying my present invention; and Fig. 2 is an end view thereof.

Referring to the drawing it will be noted

that the extinguisher shown and embodying my present invention comprises a large forward cylindrical part tapering in a graceful curve to a restricted but projecting nozzle and tapering at its rear end into a rear elongated part also cylindrical but of materially smaller diameter.

I claim:

The ornamental design for a fire extinguisher, as shown and described.

HOWARD R. ROST.
